FASTENER DEVICE

Walter I. Jones, Belmont, Mass., assignor to
United-Carr Fastener Corporation, Cambridge,
Mass., a corporation of Massachusetts

Application April 9, 1940, Serial No. 328,727

1 Claim. (Cl. 24—73)

This invention relates to improvements in fastener devices such as buckles, particularly to the type of buckle secured to the end of a strap, belt or the like, the members of which may be quickly engaged and disengaged.

An object of my invention is the provision of a simple and inexpensive buckle device, parts of which are easily engageable and disengageable but which, when in interlocking relation, are fastened against separation except by force applied to parts thereof in predetermined directions and are capable of relative rotation to accord with the movements of the wearer.

A further object of my invention relates to stud and socket members wherein the stud member has a head and neck and the socket member includes a plate portion having a stud-receiving opening of elongated shape and a spring tongue interlocking with the stud member upon moving the stud axially through the opening, the parts being disengageable by applying lifting force to the socket member at a number of points around its periphery.

Another object of my invention relates to the construction of the socket member of my device wherein the spring tongue may be readily flexed during disengagement of the parts to effect an easy separation.

Other objects and uses of my invention will be apparent from inspection of the drawing and specification hereinbelow described.

Referring to the drawing, in which I have illustrated preferred embodiments of my invention—

Fig. 1 is a front elevation of the parts of my fastener device in fastened engagement;

Fig. 2 is a sectional view of the installation shown in Fig. 1 showing movement of one fastener member relative to the other in engaging the parts;

Fig. 3 is a sectional view taken along the line 3—3 of Fig. 1;

Fig. 4 is a front elevation of one of the fastener members of my buckle device;

Fig. 5 is a side elevation of the installation shown in Figs. 1, 2 and 3 showing one method of disengaging the parts; and

Fig. 6 is a front elevation of a modified form of the fastener member shown in Fig. 4.

Although my improved buckle device is capable of a variety of uses, I have chosen to illustrate it in connection with an article such as a bathing cap wherein a socket member or buckle plate 1 carrying a chin strap 2 is connected with a stud member 3 secured to a portion of a bathing cap

4. The stud of the buckle device comprises an upstanding stud portion having a head 5 of curved contour and a neck portion 6.

The buckle plate 1 has a flat body portion 7 which may be formed to provide any suitable design and which has a pair of parallel slots 8 and 9 at one end receiving the strap 2. The body 1 has a stud-receiving opening 10 (Fig. 4) at an opposite end from the slots 8 and 9. The opening 10 is preferably of oval or elongated form so as to enable the parts of the device to be disengaged by lifting force applied to the sides of the body portion 7, as will be described. The body 7 has a locking member in the form of a spring tongue 11 normally lying in the plane of the body and extending in a direction transverse to the major axis of the opening 10. The spring tongue 11 is defined by spaced slits which extend from the opening 10 toward the slots 8 and 9 and which terminate adjacent to, but short of, the slot 8. It will be noticed that the distance between the slots 12—12 at their ends adjacent the strap-receiving slot 8 is no greater than, and preferably less than, the distance between the slots 12—12 at their ends adjacent the opening 10. As a result of this construction, the locking tongue is rendered very resilient so as to be movable laterally to increase the size of the opening 10 to effect disengagement of the parts even though relatively light lifting force may be applied to the buckle plate. The spring tongue 11 has a free edge 13 at its end adjacent the opening 10 and the body 7 has a wall 14 adjacent the opening 10 cooperating with the edge 13 to engage the neck 6 of the stud portion when the parts of the buckle are in interlocking relation. The edge 13 is preferably of concave or arc shape with the ends 15 of the edge in close proximity to the wall 14 and disposed on the same side of the center line 40 of the stud 3 extending parallel to the major axis of the opening 10.

To engage the buckle plate 1 in interlocked relation with the stud 3, the buckle plate is moved toward the stud 3 to receive the stud head 5 within the opening 10. As the opening 10 is too small to receive the stud head when the spring tongue 11 is in normal position, the tongue 11 is moved transversely outwardly through engagement thereof with the rounded cam surface of the head 5 until the opening 10 is sufficiently large to admit the head, after which the tongue 11 returns toward normal position under its natural tension to interlock with the neck 6 of the stud portion between the head 5 and the support 4. Thus the parts of the buckle are secured

against inadvertent disengagement and yet the buckle plate 1 is free to pivot relative to the stud member 3. The buckle 1 may be purposely disengaged from the stud member by grasping it at its end adjacent the strap 2 and swinging it outwardly away from the work in the direction A, shown in Fig. 3, by pivoting the plate 1 around its axis transverse to the longitudinal axis of the tongue 11 to disengage the tongue 11 from the head portion. Another very convenient way of disengaging the buckle from the stud member is to grasp the buckle at portions of its sides 16-17 and pivot the buckle around the longitudinal axis of the spring tongue 11, as most clearly shown in Fig. 6, to disengage the tongue. This method of separation of the parts results directly from the particular construction of the buckle plate 1 wherein the stud-receiving opening 10 is oval in shape. When the buckle is lifted by force exerted on one of the sides 16, the spring tongue 11 is twisted downwardly thereby enlarging the oval opening 10 to permit the head 5 to pass therethrough. In order to effect ready twisting of the spring tongue 11 during the disengaging operation, it is desirable to have the width of the tongue 11 at its end adjacent the slot 8 no wider than the width of the tongue at its end adjacent the opening 10. This method of disengaging the parts, wherein the plate member is lifted by force applied to its sides, is natural and convenient in many applications of the buckle device, as, for example, when the buckle is secured to the end of an ankle strap such as provided on certain foot apparel.

Fig. 5 represents a modification of my preferred form of buckle plate shown in Figs. 1-4 wherein I have provided a buckle plate having strap-receiving slots 17 and 18 at one end and a stud-receiving opening 19 formed in the body 20 of the buckle adjacent the slot 17 and a spring tongue 21 similar in form to the spring tongue 11 of my preferred device defined by spaced slits 22 extending from the opening 19 toward an opposite end 23 of the body 20 from that having the slots 17 and 18. My modified construction of 45

buckle plate is particularly useful in combination with straps such as used on overshoes to bring the flaps together due to the fact that in such installations it is advantageous to disengage the parts of the buckle by grasping the buckle plate at its end 23 to swing the plate out of engagement with the stud portion.

Although I have illustrated and described preferred embodiments of my invention, I do not wish to be limited thereby because the scope of my invention is best defined in the following claim.

I claim:

A fastening device for cooperation with a stud member having a circular head and reduced shank, comprising a plate member of thin metal formed with a U-shaped slot providing a relatively stiff body portion surrounding said slot, and a yielding tongue between the sides of said slot, said tongue being integrally joined to the body portion between the ends of the sides of said slot, and having a convexed free edge along the bight of said slot, the central portion of the free edge of the tongue being formed with a substantially semi-circular recess forming with the opposed edge of the bight of said slot a stud-receiving opening of substantially the diameter of the stud shank of materially less diameter than the stud head, said tongue being adapted to engage the shank of the stud and hold it against the body portion preventing shifting axially and transversely of the bight of the slot when in locked position, said tongue being yieldable transversely relative to the body portion to permit insertion and removal of the stud from the stud-receiving opening, said body portion being extended substantially beyond the bight of the slot and provided with at least one transverse strap-receiving opening, said extended strap-receiving portion also constituting a handle portion spaced from the line where the tongue is joined to the body portion a distance greater than the free edge of the tongue engaging the stud.

WALTER I. JONES.
